SEALABLE CONTAINER

Frank Keidel, Elmhurst, N. Y., assignor to The International Seal and Knot Protector Co., New York, N. Y., a corporation of New York

Application April 25, 1936, Serial No. 76,306

3 Claims. (Cl. 150—3)

The present invention relates to bags, pouches or other flexible walled containers, and more particularly to the means employed for sealing the same so that they cannot be opened without breaking the closure seals.

One object is to provide a construction which is simple and inexpensive to manufacture, easily and quickly sealed, effective to prevent unauthorized access without leaving tell-tale evidence, and easily and quickly opened upon breaking the seal.

Various other objects of the invention will be apparent from the following particular description and from an inspection of the accompanying drawing in which:—

Fig. 1 is a perspective view of a sealed container embodying the present invention, parts of said container being broken away to show the side seam and fold.

Fig. 2 is a section taken on the line 2—2 of Fig. 1.

Fig. 3 is a section taken on the line 3—3 of Fig. 2.

Fig. 4 is an end view of a portion of the sealing device.

Fig. 5 is a bottom plan view of the rigid closure member for the bag, and

Fig. 6 is a perspective view of the upper end of the bag, parts of which are shown broken away.

In the specific embodiment of the invention shown, there is provided a flat bag 10 made of strong flexible material such as canvas and open at one end to form a mouth as shown in Fig. 6. The bag is so constructed and sewed that if the seam should be broken or cut it cannot be resewed while the mouth of the bag is sealed. For that purpose, the bag is made from a blank folded to bring together the opposite side and bottom edges. These edges are sewed together to form a side seam 11 and a bottom seam 12, and the bag is then turned inside out to bring the seams inside of the bag. Thus the seams are inside and concealed, and if broken or cut by any unauthorized tampering, the bag cannot be restitched in the inside of the bag while the mouth of the bag is sealed.

The mouth portion of the bag is so constructed as to sealably receive a tubular closure member 13. For that purpose, the upper rim portion of the bag is folded inwardly and stitched to the body of the bag to form a hem 14. Extending in said hem 14 is a core rope 15 which is slightly shorter than the length of said hem 14 so that the ends of said rope terminate close to

the ends of said hem as shown in Fig. 6, and which forms a thickened or beaded rim 16 for the mouth of the bag.

As a feature of the present invention, the ends of the hem 14 are closed by means which serve not only to block access to the rope 15 but also to receive a seal. For that purpose, said means comprises a tubular rivet 17 passing through the ends of the hem 14 slightly beyond the ends of the rope 15, and having the ends upset to form an eyelet as shown in Fig. 6. This eyelet, besides having the functions referred to, also serves to effectively close the seamed portion of the mouth to thereby block access to the internal stitches of the bag through this seamed portion.

The tubular closure member 13 is provided with a longitudinal slot 18 of such width as to receive the walls of the bag adjacent to the beaded rim 16, the internal diameter of said member being such as to receive therein the two opposed portions of the beaded rim side by side. The width of each of these beaded portions exceeds the width of the slot 18, and the rope 15 is of such size and density as to render it impossible for these portions to be compressed to such an extent that they can be pulled out through the slot 18.

The tubular closure member 13 is adapted to be drawn endwise over the two opposed beaded rim sections 16 to close the mouth of the bag 10. As a feature of the present invention, this closure member 13 is made of absolutely non-bendable material, that is material which will break before it will bend. For that purpose, it is preferably of cast iron but may be made of glass, ceramic material such as porcelain, or other nonbendable material.

The forward end 20 of the slot 18 is preferably flared or enlarged to facilitate the entrance of the fold edge of the bag walls, and the walls of the closure member 13 near this forward end are provided with a pair of opposed holes 21 adapted to align with the eyelet 17 and to receive the seal 22.

The opposite or rear end of the closure member 13 is completely closed by an integral wall 23 which blocks access to the beaded rim 16 from that end of the closure member, and which also serves as a stop to predetermine the position of the holes 21 with respect to the eyelet 17 when said closure member has been drawn into closed position shown in Figs. 1 and 3. In this closed position, the holes 21 will be substantially in axial alignment with the eyelet 17, the closure

member 13 being locked in this position by means of any suitable sealing device such as the seal 22 having a shackle 24 passing through these holes and eyelets. This seal is of such a 5 character that it may be applied to connect the ends of the shackle and when applied it cannot be removed. It may be similar to those shown in my prior Patents Nos. 1,930,560 and 2,006,051.

It should be noted that the closure member 13 10 is of simple construction and can be quickly and conveniently applied to and removed from the bag 10. In closed position, this bag cannot be opened without either breaking the seal, cutting the 15 shackle, cutting the seams, or cutting the bag, and in any of these cases there will be tell-tale evidence that the bag has been tampered with. The closure member 13 cannot be bent to widen the slot 18 and to slip the beaded rim 16 out through the widened slot 18.

20 As far as certain aspects of the invention are concerned, the closure member 13 need not have an end wall and may be transversely perforated at both ends, and the bag mouth may be provided with a second eyelet corresponding to the 25 eyelet 17 but disposed on the opposite side of the bag to receive a second seal.

Having thus described my invention, what I claim as new and desire to secure by Letters Patent is:

30 1. A bag having a mouth edge which is thickened along the major portion of the length thereof and which is substantially flat along a comparatively short portion of the length thereof, and an aperture through the flat portion of 35 said edge, and a tubular closure member of non-bendable material slotted to receive the walls of said bag adjacent to said thickened edge, and having an aperture near one end to align with

said bag aperture when in closed position, said apertures being adapted to receive a seal when in said position.

2. In combination, a bag open at one end and having the upper marginal portion thereof at 5 said end folded inwardly and sewed to the bag to form a hem, a core rope in said hem serving to form a beaded mouth edge and having the ends thereof spaced from the ends of the hem, a tubular rivet passing through the ends of said hem beyond the ends of said rope, the ends of 10 said rivet being upset to form an eyelet, and a tubular closure member adapted to enclose said beaded edge and provided with a longitudinal slot to receive the walls of the bag adjacent to 15 said beaded edge, and having an aperture near one end adapted to align with said eyelet when in closed position, the other end of said closure member being closed by a wall integral with said member, said aperture and said eyelet being 20 adapted to receive a seal when said member is in said position.

3. In combination, a bag having an open end provided with a hem, a core in said hem serving to form a beaded mouth edge and having the 25 ends thereof spaced from the ends of the hem, a tubular rivet passing through the ends of said hem beyond the ends of said core, the ends of said rivet being upset to form an eyelet, and a tubular closure member adapted to enclose 30 said beaded edge and provided with a longitudinal slot to receive the walls of the bag adjacent to said beaded edge, and having an aperture near one end adapted to align with said eyelet when in closed position, said aperture and said eyelet 35 being adapted to receive a seal when said member is in said position.

FRANK KEIDEL.
